(57) **CLAIM**

The ornamental design for a pet water dispenser, as shown and described.

DESCRIPTION

FIG. 1 is a front, top perspective view of a pet water dispenser design showing my new design.

FIG. 2 is a front view of a pet water dispenser.

FIG. 3 is a rear view of a pet water dispenser.

FIG. 4 is a left side view of a pet water dispenser.

FIG. 5 is a right side view of a pet water dispenser.

FIG. 6 is a top view of a pet water dispenser.

FIG. 7 is a bottom view of a pet water dispenser; and,

FIG. 8 is a rear, bottom perspective view of a pet water dispenser.

The broken lines in the drawings depict portions of the pet water dispenser that form no part of the claimed design.
